(57) **CLAIM**

The ornamental design for a storage container, as shown and described.

DESCRIPTION

FIG. 1 is a front elevation view of a storage container, showing the new design;

FIG. 2 is a rear elevation view thereof;

FIG. 3 is a top plan view thereof;

FIG. 4 is a bottom plan view thereof;

FIG. 5 is a right side view thereof;

FIG. 6 is a left side view thereof;

FIG. 7 is a cross-section view thereof; shown along line 7-7 of FIG. 1;

FIG. 8 is a cross-section view thereof; shown along line 8-8 of FIG. 3;

FIG. 9 is a top, right, and front perspective view thereof;

FIG. 10 is a bottom, right, and rear perspective view thereof;

FIG. 11 is another top plan view thereof; shown in an alternate configuration; and,

FIG. 12 is another top, right, and front perspective view thereof; shown in an alternate configuration.

The dash-dash broken lines depict portions of the storage container that form no part of the claimed design.

1 Claim, 6 Drawing Sheets
